UNITED STATES PATENT OFFICE.

HENRY MEYER, OF DETROIT, MICHIGAN.

WATER-TREADING APPARATUS.

Application filed September 26, 1922. Serial No. 590,569.

To all whom it may concern:

Be it known that I, HENRY MEYER, a citizen of Yugoslavia, residing at Detroit, in the county of Wayne and State of Michigan, have invented certain new and useful Improvements in Water-Treading Apparatus, of which the following is a specification.

This invention relates to improvements 10 in devices for walking upon the surface of water and has as its main object to provide devices, engageable with the feet of an operator, which produce a buoyant effect enabling a person to travel with safety and 15 without immersion in the water.

Another purpose is to produce a device 20 that can be collapsed and folded into a small compass when not required for use, permitting it to be easily carried or stored. A further aim is in the provision of a 25 simple, cheap and effective apparatus, which can be easily attached and operated without difficulty to a shoe or even used as an element in a pontoon bridge.

These objects are attained by the novel 30 construction, combination and arrangement of parts hereafter described and shown in the accompanying drawings, in which:—

Figure 1 is a plan view of one of a pair 35 of like water treading apparatus as made in accordance with the invention.

Figure 2 is a side elevational view of the same.

Figure 3 is a transverse sectional view 40 taken on line 3—3 of Figure 2, drawn to an enlarged scale.

Figure 4 is a similar sectional view taken on line 4—4 of Figure 2.

Figure 5 is a fragmentary side view showing 45 the jointed frame support for the buoyant elements.

These devices, which are to be used in pairs, one for each foot, are each composed of two oppositely extending, conical elements 10 comprised of a series of hollow 50 flexible, accordion-like elements 11 gradually reduced in diameter outwardly from their bases and held in circular form by internal rib-like rings, as at 12.

The adjacent or base elements of the 55 series are attached by cords 13 to a substantially rectangular central frame 14 having rounded corners, on the upper side of which are flat horizontal plates 15 serving as foot rests and carrying loops 16 adapted to engage the shoes of an operator.

This frame 14 is also hollow and provided with valves 17 to admit air when the buoys are extended, for inflation and also arranged to deflate the same when not required for use, thus permitting collapsing 60 into a relatively small parcel.

In order to stiffen the construction when extended, a plurality of brackets 18 are attached at intervals to the opposite sides of 65 the buoy elements, these brackets carrying the inner ends of links 19 engaging clips 20 which in turn are engageable with bars or rails 21 made in short sections and joined 70 at their ends by pivot connections 22 designed to permit folding in one direction but resisting flexure in the other.

The outer or end buoy elements 23 and 24, respectively front and rear, present semi-spherical surfaces, and the rear elements are 75 provided with bands 25 the same being the terminus of the side rails 21.

Also to the face of the rear elements 24 are attached rudder-like projections 26 to assist in maintaining a straight course 80 through the water in which the devices are partially submerged, the depth to which they enter depending on the area exposed and weight of the individual using the same.

It is to be understood that the buoyant 85 elements are water tight and may be preferably made of fabric that will resist the entrance of water, the size and proportions of the several parts being suited to the function they are to perform.

Having thus described my invention and set forth the manner of its construction, application and use, what I claim as new and desire to secure by Letters Patent, is:—

1. A water treading apparatus comprising a central hollow frame, footholds carried thereby, a plurality of buoyant elements attached to the ends of said frame, said buoyant elements decreasing progressively in diameter from the frame outwardly, means controlling the admission of air to said buoyant elements, sectional rails engaging the opposite sides of said elements, means at the joint of said rails permitting 100 breaking in one direction and holding rigidly in other directions, and means for detachably engaging the adjacent sections of said elements to said frame.

2. A water treading apparatus comprising a central hollow frame substantially 110 rectangular in cross section, a foot board

on one side of the frame, foot engaging means on said board, oppositely extending buoyant members removably engaging the ends of said frame, said buoyant members consisting of a series of collapsible elements open throughout, caps at the ends of said members, a rudder attached to one of said caps, sectional rails engaging at intervals

with said members, means formed with the joints of said rails permitting turning in one direction only, and means in said frame for admitting air to said buoyant members.

In witness whereof I have affixed my signature.

HENRY MEYER.
